UNITED STATES PATENT OFFICE.

PETER G. GIROUD, OF NEWARK, NEW JERSEY, ASSIGNOR TO THE INTERNATIONAL TIME RECORDING COMPANY, OF NEW JERSEY.

PLUNGER FOR TIME-STAMPS.

SPECIFICATION forming part of Letters Patent No. 678,778, dated July 16, 1901.

Application filed April 20, 1900. Serial No. 18,594. (No model.)

To all whom it may concern:

Be it known that I, PETER G. GIROUD, a citizen of the United States, and a resident of Newark, in the county of Essex and State of New Jersey, have invented a new and useful 5 Plunger for Time-Stamp, of which the following is a specification.

My invention relates to a plunger for time-stamps, with the object in view of providing 10 a plunger which may be utilized with time-stamps of varying types at present in common use and which will prevent liability of injury to the type under unusual impulse.

It is quite common in the use of time- 15 stamps for the operator to strike the plunger a sharper blow than is necessary for securing the impression, the purpose being to be sure and get a clear impression, the party not realizing that a blow may be struck which 20 will injure the type.

My present invention is directed to the structure and mounting of a plunger which will successfully resist such unnecessarily sharp blows from the hand of the operator 25 and spare the damaging of the type, even though the blow be unusually severe.

A practical embodiment of my invention is represented in the accompanying drawings, in which—

30 Figure 1 is a front view of the plunger, showing it in position with relation to a group of type-wheels. Fig. 2 is a side view of the same, and Fig. 3 is a partial vertical section from front to rear.

35 The impression-platen is denoted by A. It is faced with some suitable yielding material a—such, for example, as rubber—and is provided with a socket a' on its back, through which a set-screw a² extends for the purpose 40 of removably securing the platen to the lower end of the plunger.

The plunger-rod is denoted by B. The connection between the socket on the back of the platen A and the plunger-rod B is made by 45 means of a sleeve C, the lower end of which is fitted to enter the socket a' on the back of the platen. The plunger-rod is provided with a pin b, extending laterally therefrom through an elongated slot c in the sleeve C and also 50 through an elongated slot d in the front of the hollow head D of the overhanging supporting-

arm E, which is intended to be secured to the supporting-frame in position to maintain the impression-platen opposite the type-wheels of the stamp. The pin b is conveniently screw-threaded and provided with a kerf in its head for the purpose of removing it at pleasure. 55 The sleeve C is intended to fit and slide easily within the enlarged bore in the lower part of the head D, and the plunger-rod B is intended to slide with an easy-sliding fit within the sleeve C, the sliding movement of the plunger-rod within the sleeve C being limited in extent by means of the pin b extending through the slot c in the sleeve C. 60 65

A stiff spring F, inserted within the sleeve C below the plunger-rod B, serves to hold the rod at the limit of its upward movement relative to the sleeve C and serves to form a yielding cushion between the said rod and 70 the impression-platen when the said rod is depressed to force the record-receiving strip into contact with the type and printing-ribbon. A nut f, screwed into the lower end of the sleeve C, serves as a keeper to hold the 75 spring in place when the platen is removed.

The plunger-rod B intermediate of its ends is fitted to slide vertically within the contracted portion d' of the bore in the head D, and the said plunger-rod, sleeve, and platen 80 are normally lifted or out of contact with the record-receiving strip, ribbon, and type by means of a coil-spring H, located around the plunger-rod within the upper enlarged bore of the head D, the lower end of the spring 85 bearing against a shoulder d² within the said head D and its upper end bearing against the lower end of the socket g, depending from the handle G. The upper end b' of the plunger-rod is screw-threaded and adapted to screw 90 into the interiorly-screw-threaded socket g. The handle is conveniently provided with a depending cylindrical guard g', which is intended to surround the upper portion of the head D and protect the interior of the said 95 head from dust and foreign matter.

In operation the stroke of the hand on the handle G first depresses the platen A into contact with the record-receiving strip, ribbon, and type against the tension of the 100 spring H, and when the platen comes in contact with the record-receiving strip, ribbon,

and type the continued downward movement of the plunger-rod B under the impulse of the stroke on the handle will be opposed to the tension of the spring F, and hence will 5 be of yielding nature, so that no sudden or abrupt jar or stroke on the type can be made possible.

As a matter of experience it is found that a violent stroke with all the power that the operator can use without injury to the hand will not injure the type, because of the final cushioning effect which the stroke is given.

It is obvious that changes might be resorted to in the form and arrangement of the 15 several parts without departing from the spirit and scope of my invention. Hence I do not wish to limit myself strictly to the structure herein set forth; but

What I claim is—

20 The combination with a plunger-rod support and a support for the article to be operated upon, of a reciprocating plunger-rod, a

retracting-spring intermediate of the plunger-rod and its support, an impression-platen carried by the rod and a cushion intermediate of 25 the plunger-rod and impression-platen for permitting the plunger-rod to move relatively to the platen, the limited downward stroke of the plunger-rod being materially greater than the distance between the normal position of 30 the impression-platen and the article to be operated upon whereby the impression-platen is applied yieldingly to the article to be operated upon no matter how great the force of the downward stroke of the piston-rod may 35 be, substantially as set forth.

In testimony that I claim the foregoing as my invention I have signed my name, in presence of two witnesses, this 19th day of April, 1900.

PETER G. GIROUD.
